UNITED STATES PATENT OFFICE.

ALEXANDER DOM, OF MOUNT HEALTHY, ASSIGNOR TO THE GLOBE COMPANY,
OF CINCINNATI, OHIO.

BINDER FOR FILE-CASES.

SPECIFICATION forming part of Letters Patent No. 498,744, dated May 30, 1893.

Application filed March 8, 1893. Serial No. 465,163. (No model.)

To all whom it may concern:

Be it known that I, ALEXANDER DOM, a citizen of the United States, residing at Mount Healthy, Hamilton county, State of Ohio, have 5 invented certain new and useful Improvements in Binders for File-Cases, of which the following is a specification, reference being had to the accompanying drawings.

The object and nature of my invention will 10 be apparent from the description and claims hereinafter set forth.

In the accompanying drawings:—Figure 1, is a perspective view of my improved binder in an operative position within a file-case, the 15 latter being partially broken away while the index is indicated by dotted lines. Fig. 2, is a side elevation of my improved binder detached from the file-case and index, and Fig. 20 3, is a rear perspective view of said binder. Fig. 4, illustrates the binder attached to a file-case having a T-shaped groove in the back thereof instead of the flanged plate shown in Fig. 1.

My improved binder consists of a rod A 25 upon which the separable leaves or partitions, B, of the index are filed, said rod being provided with a plate C, which latter is adapted to detachably connect with the inner face of the file-case, as will presently appear.

30 The filing-rod, A, is preferably bent upon itself to form the end angular portions a , a^2 , and parallel portion a^3 , to which latter portion the plate C is attached, as shown. This plate is preferably provided with a central 35 longitudinal groove b formed therein, within which a portion only of the rod a^3 is soldered or otherwise suitably connected; but, this groove might be dispensed with without departing from my invention.

40 The essential feature of my invention consists in attaching a portion only of plate C to rod a^3 , the remaining portion of said plate being sprung away from said rod.

In Fig. 1, D, represents a plate having in- 45 turned flanges, d , along its longitudinal edges, the object of said flanges being to grasp and retain the plate C when the latter is slid to place, as shown. The plate, D, is attached to the inner face of the filing-case (preferably 50 the back, E,) in any desired manner.

I will now describe the operation of my im-

proved binder. The rear portion of each index leaf, B, is provided with a perforation, b^2 , through which the filing-rod, A, is passed, the latter being sprung out for this purpose as 55 shown by dotted lines in Fig. 2. After all the index leaves are filed upon their rod, the latter is then sprung inward and engages with the hook a^4 on the outer end of portion a^2 , as shown, at which time said index and its binder 60 are placed within the filing-case. The binder is attached within said case by sliding the outer longitudinal edges of plate C within the groove formed by the inturned flanges d ; and, a portion of said plate being sprung away 65 from its rod a^3 , said bent-away portion will bind against the inner face of said flanges, thus securing and providing a firm yet detachable connection between the index and file-case, which is very desirable. Heretofore, 70 binders having a filing-rod and a flanged or winged - back adapted to slide within a T-shaped groove in the back of the case, have been provided with wedge - shaped ledges which are forced into said groove at one or 75 both sides of the back of the binder, in order to secure a firm connection for the latter; but, these ledges, being separate from the binder, are liable to get lost or misplaced, and are, furthermore, expensive of manufacture. 80

The above, and other objectionable features which might be enumerated, are obviated by the use of my improved binder, which latter will also operate and bind within the ordinary T-shaped groove in the back of a file-case, as 85 shown in Fig. 4.

What I claim as new, and desire to secure by Letters Patent, is—

1. The filing-rod A having a rear parallel portion a^3 , and a plate C attached to the latter 90 for a portion of its length, the remaining portion of said plate being sprung away from its support, the said plate being adapted to be detachably connected with a file-case as set forth.

2. A binder for a file-case, the same consisting of a filing-rod having a rear portion or support a^3 , with a plate attached centrally thereto for a portion of its length, the remaining portion of said plate being sprung away 95 from said support, in combination with a flanged plate attached to the file-case, as and for the purposes set forth.

3. As a new article of manufacture, a binder for a file-case, the same consisting of a filing-rod A bent upon itself to form the end angular portions a and a^2 and parallel rear portion 5 a^3 , the latter having a plate C attached thereto for a portion of its length, the remaining portion of said plate being sprung away from its support, as set forth.
4. The rod A bent upon itself to form the 10 end angular portions a , a^2 , and rear parallel portion a^3 , in combination with plate C hav-

ing a central longitudinal groove b therein, a portion of said plate within said groove being attached to the rear portion a^3 of the filing-rod, the remaining portion of said plate being 15 sprung away therefrom, and suitable means for detachably connecting said plate to a file-case.

ALEXANDER DOM.
